CABLE OPERATED BOTTOM GATE FOR A HOPPER

Robert G. Le Tourneau, Longview, Tex.

Application February 27, 1952, Serial No. 273,575

3 Claims. (Cl. 298—35)

This invention relates to hopper type trailers, semi-trailers, wagons and similar material handling apparatus of that type adapted for transporting bulky materials such as earth, coal, gravel, etc., and having a hopper bottom through which the entire load may be discharged.

Heretofore it has been the practice to rely on gravity for either opening or closing the bottom gates. Various types of hydraulic systems have also been used for controlling the opening or closing of the bottom gates. In those systems which rely on gravity to close the gates, one of the difficulties encountered is that gravel, stones and other heavy objects become lodged between the gates and keep them from closing securely. Another problem is that some type of latch or closure device is required to keep the gates closed during the loading operation.

In those systems which rely on hydraulic means for opening or closing the gates, one of the problems has been the impracticability of designing an economical system capable of delivering to the gates the high power desired for operating them at a fast rate of speed. Another problem found in hydraulic systems is the high cost of maintenance of hose and pumping mechanisms.

One of the objects of my invention is, therefore, to provide a cable operated system for supplying a power open and power close to the bottom gates of a hopper.

Another object of my invention is to provide power closed gates which will overcome resistance offered to their closing by stones, gravel or other heavy objects.

Another object of my invention is to provide an economical yet fast acting cable power system for opening and closing bottom gates.

Another object of my invention is to provide such a system in which the maintenance of the components is simple and economical.

Another object of my invention is to provide a dump gate opening and closing system which does not require latches or closure devices to keep the gates in a closed position.

Other objects and advantages of the invention will become apparent upon perusal of the following detailed description taken in connection with the accompanying drawings. While I have shown and described herein a preferred embodiment, it is to be understood that the same is susceptible of modification and change without departing from the scope and spirit of my invention.

In the drawings,

Fig. 1 is a side elevation of a tractor and hopper type semi-trailer embodying my invention.

Fig. 2 is an enlarged view of the rear end of the hopper body with the bottom gates closed. For purposes of clarity Figs. 2 and 3 are shown without the wheels and frame support members.

Fig. 3 is an enlarged view of the front end of the hopper body with the bottom gates closed.

Fig. 4 is an enlarged fragmentary view of a double sheave housing.

Fig. 5 is an elevation of the same double sheave housing.

Fig. 6 is an enlarged view of the double drum showing cables wound thereon.

Fig. 7 is an end view of the same drum.

Fig. 8 is a diagrammatic view on a reduced scale of the rear end of the hopper body, illustrating the bottom gates in the open position.

Referring to the drawings in detail, the letter A designates a hopper type semi-trailer constructed in accordance

2

with this invention, and B is a two-wheel tractor to which it is coupled.

While my invention has been shown by way of example, embodied in a semi-trailer, it is to be understood that the invention may be equally well embodied in various other vehicle constructions, such for instance as full or four wheel trailers, railway cars, etc.

In the example shown, the trailer A comprises a hopper 1 welded at its rear to frame members 2, 3, 4 and 5 which are in turn supported by a pair of rear wheels 6 (only one appears in the drawings), the hopper being welded at its front to yoke 7 and struts 8 and 8b which are in turn pivotally connected by steering assembly 9 to tractor B.

Hopper 1, which is open at the top and bottom, is provided with vertical end walls 10 and 11, and downwardly converging side walls 12 and 13 which have vertical portions 14 and 15. Welded along side walls 12 and 13 are longitudinal channels 16 and 17. Channel 16 has mounted at its rear sheave housings and sheaves 18 and 19, and at its forward end sheave housings and sheaves 20 and 21. In like manner channel 17 has sheave housings and sheaves 22 and 23 mounted at its rear and sheave housings and sheaves 24 and 25 mounted at its forward end.

Rear wall 10 has welded thereto brackets 26, 27 and 28 and gate hinge ear 29. Reversible motor 30 (capable of delivering 50 horsepower) and gear box 31 are secured between brackets 27 and 28 and over hinge ear 29

30 by welding. Rotatably attached to gear box 31 is a double winding drum 32 (shown enlarged in Fig. 6) having smooth winding surfaces 33 and 34 separated by flange 35. Also welded to rear wall 10 is a group of sheave housings designated by reference numerals 36, 37, 38, 39, 40, 41 and 42, each housing having rotatably mounted therein one or more sheaves, part of which are referred to in detail hereinafter. Pivoted supported by pins 43 and 44 are pivot arms 45 and 46 to which are welded oppositely swinging bottom gates 47 and 48. Welded to arms 45 and 46 are channels 49 and 50, on each of which is secured a double sheave housing. An enlarged view of one such double housing 51 is shown in Figs. 4 and 5 wherein numerals 52 represent bolts securing the housing to channel 65.

45 Front wall 11 has welded thereto yoke 7 and gate hinge ear 53. Cable tightening mechanisms 54 and 55 and cable deadend pipes 56 and 57 are also secured to wall 11 by welding. Sheave housings 58 and 59 are welded to wall 11 below hinge ear 53. Front pivot arms 60 and 61 are pivotally mounted by pins 62 and 63 in the hinge ear 50 and have welded thereto gates 48 and 47 respectively. Welded to front arms 60 and 61 are channels 64 and 65, each of which serves as a mounting for a double sheave housing identical with that shown in Figs. 4 and 5.

55 Cable reeving

Wound on double drum 32 are four cables 66, 67, 68 and 69. Cable 66 is dead-ended near one end of the drum by set screw 70 bearing against bracket 71, and thence extends in a clockwise direction (looking at Fig. 7) around the drum for a plurality of turns, thence off the drum. Cable 67 is dead-ended on the drum near flange 35 by set screw 72 bearing against bracket 73 and thence extends around the drum in a counterclockwise direction for a plurality of turns until drum surface 33 is substantially full of one layer of cable (consisting of cables 66 and 67), thence off the drum. After leaving the drum surface, cable 67 extends to and around sheaves 74, the inner sheave of channel 49, and sheave 76, thence to and around sheaves 18 and 20 along side wall 12, thence to the first wall 11 to and around sheave 77, to and around inner sheave 78 of channel 65, thence to dead-end on pipe 57.

Cable 66, after leaving drum surface 33, extends to 75 and around sheaves 79, 80 and 81, thence to and around sheaves 19 and 21 along side wall 12, thence around outer sheave 82 of channel 65 to dead-end on rod 83 of cable tightening mechanism 55. Cable tightening mechanism 55 comprises handle 84, worm 85 and ratchet 86 which 80 engages rod 83. Upon rotation of handle 84, cable 66 may be tightened.

Cables 68 and 69 are dead-ended on drum 32, wound in opposite directions on drum surface 34 until the surface is substantially full of a single layer of cable, and are thence reeved through a system of sheaves and dead-ends in a manner identical with that described for cables 66 and 67 but on the opposite side of the longitudinal center line of the hopper. Just as 66 and 67 cooperate with channels 49 and 65 to control gate 47, so cables 68 and 69 cooperate with channels 50 and 64 to control gate 48.

Operation

Upon rotation of drum 32 in a counterclockwise direction (looking at Fig. 1 or Fig. 7), cable 67 will wind off of drum surface 33 and cable 66 will wind onto the drum surface occupying the same space vacated by the unwinding cable. As cable 66 reels in and cable 67 pays out, channels 49 and 65 and pivot arms 46 and 61 will be moved outwardly from the longitudinal center line of the hopper and will open bottom gate 47. The open position of gate 47 is shown in Fig. 8.

Rotation of drum 32 in the direction indicated above will at the same time cause cable 69 to wind off of drum surface 34 and cable 68 to wind on in the same space vacated by the unwinding cable. As cable 68 reels in and cable 69 pays out, channels 50 and 64 and pivot arms 45 and 60 will move outwardly from the longitudinal center line of the hopper and will open bottom gate 48. The open position of gate 48 is shown in Fig. 8. Thus, it may be readily observed that gates 47 and 48 are power opened by cable means.

Upon rotation of drum 32 in the opposite direction (clockwise looking at Fig. 7) each cable winds on the drum in a direction opposite to that described above, and gates 47 and 48 will be positively moved to a closed position. Thus, it may readily be observed that gates 47 and 48 are power closed by cable means.

From the description of my invention it may readily be seen that the objects set forth have been fulfilled.

What I claim and desire to secure by Letters Patent is:

1. In a bottom opening hopper having side walls, a front wall and a rear wall, a pair of oppositely swinging gates comprising the bottom of said hopper, said gates being attached to a pair of arms pivotally mounted on said front wall and a pair of arms pivotally mounted on said rear wall, a double sheave housing having a pair of sheaves mounted therein and fixed on each of said arms, a plurality of fixed sheaves mounted in spaced relation on the walls of said hopper, reversible power means having a double surface winding drum attached thereto mounted on said rear wall, a first pair of cables each

dead-ended on one of said surfaces and oppositely wound thereon and thence reeved through certain of said fixed sheaves and certain of said arm sheaves to dead-end on said front wall, and a second pair of cables each dead-ended on the other of said surfaces and oppositely wound thereon and thence reeved through certain other fixed sheaves and certain other of said arm sheaves to dead-end in a cable tightening mechanism mounted on said front wall, thereby upon rotation of said power means in

10 one direction said gates will open and upon rotation of said power means in the opposite direction said gates will close.

2. In a wheeled vehicle, a main frame having a hopper mounted thereon, oppositely swinging bottom opening gates pivotally connected to said hopper, and a constant tension cable winding system for power opening and power closing said gates, said system comprising a double surface drum adapted for reversible rotation, a first pair of cables each dead-ended on one of said surfaces and

15 oppositely wound thereon and thence associated with one of said gates, a second pair of cables each dead-ended on the other of said surfaces and oppositely wound thereon and thence associated with the other of said gates, and cable tightening means for maintaining said cables substantially taut at all times.

3. In a wheeled vehicle, a main frame having a hopper mounted thereon, oppositely swinging bottom opening gates pivotally connected to said hopper, and a constant tension cable winding system for power opening and

20 power closing said gates, said cable winding system comprising reversible power means mounted on said hopper, a double winding drum driven by said power means and having two pairs of cables wound thereon, pivot arms secured to said gates and pivotally mounted on said hopper, sheave housings having sheaves mounted therein fixed on said hopper, and sheave housings having sheaves mounted

25 therein fixed on said pivot arms, said cables being reeved between said drum and said sheaves so that upon rotation of said drum in one direction, said gates are opened and

30 upon rotation of said drum in the opposite direction, said gates are closed.
